UNITED STATES PATENT OFFICE

104,734

DESIGN FOR A FOLDING COT

Arthur Wesley, Chicago, Ill., assignor to Burton-Dixie Corporation, Chicago, Ill., a corporation of Delaware

Application January 15, 1937, Serial No. 67,078

Term of patent 7 years

To all whom it may concern:

Be it known that I, Arthur Wesley, a citizen of the United States, residing at Chicago, in the county of Cook and State of Illinois, have invented a new, original, and ornamental Design for Folding Cots, of which the following is a specification, reference being had to the accompanying drawings, forming part thereof.

In the drawings:

Figure 1 is a perspective view of the cot in operative position showing the new design; and Figure 2 is a perspective view of the same cot in folded condition.

I claim:

The ornamental design for a folding cot as shown and described.

ARTHUR WESLEY.
